MULTIPOLE CIRCUIT BREAKER

Paul M. Christensen, West Orange, N. J., assignor
to Federal Electric Products Company, Newark,
N. J., a corporation of Delaware

Application August 24, 1950, Serial No. 181,223

33 Claims. (Cl. 200—116)

1

This invention relates to multi-pole circuit breakers and to actuating and tripping devices therefor. More particularly, but without restriction, the invention is concerned with a multi-pole circuit breaker which can be manually opened and closed and which is also opened automatically at all of the poles upon the occurrence of an overload in the circuit of any one of the poles.

In general, the individual circuit breaker mechanisms are of the type disclosed in U. S. Patents Nos. 2,174,669, 2,209,319, 2,209,352, 2,209,353, Re. No. 23,188 and the copending applications of Thomas M. Cole, Ser. No. 127,433, filed November 15, 1949, and Ser. No. 184,749 filed September 14, 1950, both assigned to the assignee hereof.

A multi-pole circuit breaker, which represents a further development of the multi-pole circuit breaker of the present invention, is claimed in the copending application, Serial No. 181,224, filed simultaneously herewith, by myself and Alexander R. Norden, as joint inventors, and assigned to the assignee of the subject application.

The primary object of the present invention is the provision of a multi-pole circuit breaker which is opened automatically at all of the poles upon the occurrence of an overload in the circuit at any one of the poles and which is automatically reset, upon the tripping thereof, for manual movement to the closed condition thereof without requiring an additional resetting operation.

Another object is the provision of a double pole circuit breaker of the above stated type of generally simplified construction and operation.

The above and other objects, features and advantages of the present invention will be more fully understood from the following description considered in connection with the accompanying illustrative drawings.

In the drawings:

Fig. 1 is a top view of a multi-pole circuit breaker pursuant to the present invention, the circuit breaker being in the closed or circuit making condition;

Fig. 2 is a side view of the circuit breaker;

Fig. 3 is an end view of the circuit breaker;

Fig. 4 is a view similar to Fig. 1 with the cover of the circuit breaker housing removed;

Figs. 5 and 6 are sectional views taken on the lines 5—5 and 6—6, respectively, of Fig. 1;

Fig. 7 is a sectional view taken on the line 7—7 of Fig. 4;

2

Fig. 8 is a sectional view taken on the line 8—8 of Fig. 5;

Fig. 9 is a fragmentary sectional view taken on the line 9—9 of Fig. 6;

Fig. 10 is a fragmentary sectional view taken on the line 10—10 of Fig. 9;

Fig. 11 is a fragmentary view similar to Fig. 5, illustrating the disposition of one of the circuit breaking mechanisms immediately after the tripping thereof;

Fig. 12 is a sectional view taken on the line 12—12 of Fig. 11;

Fig. 13 is a sectional view taken on the line 13—13 of Fig. 12;

Fig. 14 is a view similar to Fig. 5 showing the circuit breaker mechanism in the open condition thereof;

Fig. 15 is a view similar to Fig. 5 illustrating another embodiment of the invention, a portion 20 thereof being broken away;

Fig. 16 is a fragmentary sectional view taken on the line 16—16 of Fig. 15; and

Fig. 17 is a fragmentary sectional view, on an enlarged scale, taken on the line 17—17 of Fig. 15.

Referring now to Figs. 1 through 14 in detail, the multi-pole circuit breaker 20 of the present invention is provided with the housing or casing 22 which comprises the body part 24 and the cover part or closure 26 therefor, said parts being preferably molded from a suitable insulation material, such as, for example and not by way of limitation "Bakelite." As here shown, the body part 24 is provided with an integral portion 28 (Figs. 6, 8 and 12) upstanding from the bottom thereof and disposed intermediate the opposing side walls 30 and 32 of the body part. It will be noted that said portion 28 is disposed parallel to said side walls and that the ends thereof are spaced from the opposing end walls 34 and 36 of said body part, said portion 28 serving as a partition member and, in cooperation with said side walls 30 and 32, defining within said body part the longitudinally extending chambers 38 and 40. At one end of each of said chambers, the body portion is provided with the wire terminals 42 and 44, respectively, each of said terminals being provided with a terminal screw 46 and with the depending portion 48 (Figs. 5 and 7) which extends into one of said chambers and on which there is provided a stationary contact 50. At the other end thereof, each of said chambers is provided with a terminal 52 provided with a terminal screw 54 and with a depending portion 56 which extends into

the companion chamber and to which there is secured one end of a flexible conductor 58. The cover part 26 is removably secured to the body part in any suitable manner, as for example by screws 60 which are threaded into the bores 62 5 provided in the body part. A strap 64 is secured to said cover by said screws 60, for flush mounting the circuit breaker or for mounting the circuit breaker in a suitable enclosure.

A circuit breaker mechanism 66 is mounted in 10 each of the chambers 38 and 40, respectively, and, as each of said mechanisms is similar in construction, a description of one of said mechanisms will be sufficient to describe both of said mechanisms. The circuit breaker mechanism 66 is provided 15 with a movable contact or switch member 68 which comprises the members 70 and 72, preferably formed of insulating material, and the conducting member 74. As here shown, the conducting member 74 is secured between the insulated members 70 and 72 as by the pins or rivets 76 and 78, said conducting member extending axially outwardly of said insulated members and being provided with the movable contact 80 at the free end thereof which is engageable with and disengageable from the companion stationary contact 50. The contact member 68 is pivotally mounted 20 between the ends thereof, a transverse pivot pin 82, here shown as a screw threaded member, extending from each of the side walls of the body part through the companion movable contact member and into an aperture 84 provided in each of the surfaces of said portion 28 in opposition to said side walls. The conducting portion 74 is provided with an integral depending portion 86 25 (Fig. 7) on which there is mounted a conducting part 88, said portion 86 being preferably bent over or riveted to said part 88. Part 88 is provided with a downwardly offset portion 90 to which there is welded, or otherwise secured, one end of a flexible thermostatic element 92, here shown as a bimetallic strip, which is secured adjacent the free end 94 thereof to the other end of the heretofore mentioned flexible conductor 58.

A handle or operating member 96 is provided, this being formed of an insulating material and having securely mounted therein the rigid parts 98 and 100 which together constitute a rigid link 102. As illustrated in Fig. 8, portions of said parts 98 and 100 are mounted in the handle 96 and are disposed in abutment therein, each of said parts being provided with a depending portion 104 and 106, respectively, which is offset laterally outwardly thereof and which extends outwardly from a cavity 108 (Fig. 6) formed in the handle. A transverse pivot pin 110 is disposed in the bearing notches 112, 112 which are in registry and are formed in the upper edges of the side walls of the body part, said pin extending through aligned apertures 114, 114 formed in said depending portions, respectively, for pivotally mounting the handle 96. The cover part cooperates with the pivot pin 110 to hold it in place in the bearing notches. A portion of handle 96 extends through an opening 116 provided therefor in the cover part and through an opening 118 provided in strap 64 in registry with said opening 116 so as to be accessible for convenient manual operation. The handle is also provided with the lower portions 120 and 122 which are adapted to contact the partition member 28. More specifically, said member 28 is provided at the top thereof with an integral channel portion 124 (Fig. 8) which is beveled on the ends thereof as at 126 and 128, the aforementioned handle part

120 contacting the beveled portions 126 and the aforementioned handle portion 122 contacting the beveled portions 128 to limit the movement of the operating member in both directions.

The contact members 68 and the operating member 96 are biased for movement toward their open circuit positions, the biasing of these members being effected by means of the springs 130 and 132. Each of said springs is shown as being a coil spring having extending end portions which are entered, respectively, in holes 134, 134 formed in the movable contact members and in bearing apertures 136, 136 formed in the laterally extending portions 138, 138, respectively, of the handle. The springs tend to open or separate, thus tending to move the contact members 68 in a counter-clockwise direction, viewing Fig. 5, and to move the operating member 96 in a clockwise direction.

In order that the operating member 96 may operate the contact members 68 of each of the circuit breaker mechanisms, there is provided a connecting mechanism which includes an actuator or lever 140 on each of the movable contact members. The actuator is pivotally connected with the movable contact member near the end thereof which is remote from the end carrying the movable contact 80. More specifically, the parts 70 and 72 are each provided with an upwardly extending portion 142, a pivot pin 144 being mounted between said projecting portions and the levers 140 being mounted for pivotal movement on the respective pins 144. Said parts 70 and 72 are also respectively provided with the axially extending portion 146, a pin 148 being mounted between said portions 146 and serving as a detent to retain the lever against pivotal movement of the lower portion 150 thereof outwardly of the companion movable contact member. The actuator or lever is controlled by means of the aforementioned bimetallic element 92 which is bodily movable with the movable contact member and which serves in and of itself as a latch cooperating directly with the portion 150 of the actuator. A screw 152 which is threaded through the depending part 90 and the end of flexible member 92 which is secured thereto serves to calibrate the circuit breaker mechanism by regulating the degree of overlap of lever portion 150 relative to end 94 of said bimetallic element.

In order to connect the handle 96 to the levers 140, 140, a link 154 is provided. Said link is preferably formed of insulating material and interengages said levers. More specifically, each of said levers is provided at the upper end thereof with a bearing aperture 156, said link 154 being provided at each end thereof with an axially extending portion 158 of reduced diameter which is engaged in said apertures 156, respectively. Said link is provided also with the portions 160 and 162 of greater diameter and with an intermediate portion 164 therebetween of reduced diameter. The aforementioned depending parts 104 and 106 of the rigid link 102 are each provided with a slotted portion 166 (Fig. 10), a pivot pin 168 (Fig. 9) extending between said slots 166 and being mounted for movement axially thereof to constitute a lost-motion connection. Provision is made for biasing said pin 168 in said slots in a direction outwardly of said portions 104 and 106 to provide contact pressure at each pole in the circuit closed condition of the circuit breaker. In this connection there is provided the spring members 170 and 172 which are disposed in chan-

nel 124 of part 28, one end of said members being secured in an aperture 174 provided in said portions 104 and 106, respectively, and the other end of said spring members being hooked about the pivot pin 168 inwardly of said portions 104 and 106, respectively. The link 192 is connected to the link 154 through the pivoted link member 176. As illustrated in Figs. 6 and 9, link member 176 is apertured at one end thereof, as at 178, and pivot pin 168 extends through said aperture, the spring members 170 and 172 being disposed between the link 176 and the link parts 104 and 106, respectively, as in Fig. 9. As illustrated in Fig. 10, said springs 172 and 174 bias the pivot pin 168 to the end of slot 166 adjacent the free end of members 104 and 106, respectively. At its other end, said link member 176 is provided with a bifurcated portion 180 in which the interengaging link or member 154 is pivotally mounted. More specifically, said link member 176 is formed of a suitable spring metal, the space between the free ends of the bifurcations 182, 182 being less than the diameter of reduced portion 164 of member 154. It will be noted that said bifurcations are arcuate in form and that the diameter of the space therebetween, inwardly of the free ends 182 thereof, is greater than the diameter of said portion 164. Due to the spring material of which member 176 is formed, member 154 may be mounted in link 176 by urging the center portion 154 thereof inwardly between the free ends 182 of the bifurcations for mounting member 154 as indicated in Fig. 4. It will be noted, as illustrated in Fig. 6, that the portion 164 fits with a slight clearance in bifurcated portion 180 whereby said member 154 is free to pivot on the link 176. As is also illustrated in Fig. 4, it will be noted that there is a clearance between the bifurcated portion 180 and the adjacent ends of the portions 160 of member 154 whereby the latter is permitted slight movement transversely of the link 176 to permit the said pivotal movement thereof. From the foregoing, it will be understood that the connection of portion 154 in the bifurcated portion 180 constitutes a universal 45 joint.

With the circuit breaker mechanism in the normally closed circuit position, as illustrated in Figs. 5 and 6, the pivotal axis at the pivot pin 168 is above a straight line connecting the pivotal axes at pivot pin 118 and at portion 164 of the member 154, the link 192 thus cooperating with the link 176 to form a normally locked or overset toggle in said closed position. With the circuit breaker mechanisms in said closed circuit position, the movable contact members 63 are biased in the counter-clockwise or circuit opening direction by means of the springs 130 and 132, respectively, the handle 96 is biased in the clockwise or circuit opening direction by means of the same springs, and the springs 170-172 operate at the lost motion connection of pin 168, through the link 176, the link 154, the actuators 140 and the switch members 63 to resiliently urge the movable contacts against the stationary contacts to provide contact pressure. However, actual movement in the circuit opening direction is normally prevented by reason of the described overset toggle relationship between link 192 carried by handle 96 and the link 176, it being understood that the actuating members 140 being in latched engagement with the flexible strips 92, respectively, normally hold said actuators from relative movement in the clockwise direction. Normally the handle 96 may be moved to move

the contact members in either direction and thus open or close the circuit.

Assuming that there is an overload, or other abnormal current condition, in the circuit to which the circuit breaker disposed in chamber 40 is connected, the current passing through the contacting portion 14 of the movable contact member thereof and the companion flexible strip 92 will heat the latter sufficiently to flex the latter out of engagement with the companion actuator 140. When the actuator is no longer held by the latch, the entire contact member is moved by the spring 130 to its open circuit position, as shown in Fig. 14, the actuator 140 and the link 176 assuming the relative positions shown in said figure. It will be noted that the actuator first moves in a clockwise direction, as illustrated in Fig. 11, causing the interengaging link member 154 to pivot, as indicated in Fig. 12. More particularly, as the spring 130 moves the movable contact member in a counter-clockwise direction disengaging the movable contact 80 from the companion stationary contact 58, the handle 96 is rotated in a clockwise direction by said spring 25 to assume the position illustrated in Fig. 14, the toggle collapsing and the actuator rotating in a counter-clockwise direction to the position indicated in said figure. Immediately upon the unlatching of the actuator 140 and the companion flexible member 92, the tripped circuit breaker is in the position illustrated in Fig. 11. As a result of the upward and outward movement of the engaged portion 153 of link 154 in said tripped circuit mechanism, said link 154 pivots in the link 176, as illustrated in Fig. 12, whereupon portion 158 in the untripped side tends to move in a counter-clockwise direction and spring 132 is thereupon effective to rotate the contact member in the companion circuit breaker for tripping the latter, as illustrated in Fig. 13. It will be noted that the actuator of said latter circuit breaker remains in latched engagement with the flexible member 92 thereof.

Upon the movement of the individual circuit breakers to the circuit open position, it will be noted that the multi-pole circuit breaker 20 is automatically reset to be manually moved to the circuit closed condition thereof without requiring any additional resetting operation. More particularly, in the overloaded circuit, during the movement of the parts from the position thereof in Fig. 5 to the position thereof in Fig. 14, the actuator 140, as previously described, is initially rotated in a clockwise direction as illustrated in Fig. 11, and is then rotated in a counterclockwise direction by the operation of the toggle to the position indicated in Fig. 14. It will be understood that the stop member 148 prevents the overtravel of the actuator in said counterclockwise movement thereof, and that the link 176 is free to move during the actuator movements, the pivot pin 168 moving along the slots 166 against the bias of springs 170 and 172, said springs returning the pivot pin and the link 176 carried thereby to the position illustrated in Fig. 14. The companion circuit breaker assumes the position shown in Fig. 13. Both circuit breakers are then adjusted to the "on position" by movement of the member 96 from the position illustrated in Fig. 14 to the position illustrated in Fig. 5 during which movement the movable contact members are rotated into engagement with the stationary contact members. Due to said movement of member 96, link 176 is moved from its position in Fig. 14 to its position in Fig. 5 carrying connecting

member 154 toward end wall 34 for pivoting levers 140 in a clockwise direction. As illustrated in Fig. 13, the lever 140 in the companion circuit breaker is latched to member 92 in the "off" position thereof, the lever 140 in the previously overloaded mechanism being disengaged from the companion member 92 in said position, as illustrated in Fig. 14. As handle 96 begins to move to "on" position, lever 140 in the latter mechanism engages the companion member 92 and 10 the pivotal movement of said levers, resulting from the movement of link 176, rotates both movable contact members 68 into engagement with the companion stationary contacts 50, the toggle being overset by the movement of member 96, as previously described.

The circuit breaker mechanisms of the present invention are of the trip-free type and will open upon the occurrence of an overload in either one or both thereof, even if handle 96 is held in the 20 "on" position. As previously described, upon the unlatching of strip 92 from the companion actuator 140 in the overloaded circuit, the spring thereof is effective to rotate the companion movable contact member to disengage the contacts thereof. Due to the pivoting of link 154, the end thereof in the companion circuit breaker tends to move in the same direction as the movable contact member thereof so that the biasing spring thereof is then effective to move the movable contact member and the companion actuator, as one unit, to the circuit-open position.

In the embodiment illustrated in, Fig. 15, 16 and 17, the circuit breaker construction has been modified by substituting the springs 184, 35 186 and 198 for the springs 130 and 132, respectively. Springs 184 and 186 are spiral springs having the end portions 188 and 190, respectively. Each of said springs 184 and 186 is mounted on a pivot pin 192 which extends through the movable contact member 68, one end of said pins being disposed in a grooved portion 194 formed in the casing side walls 30 and 32, respectively, and the other end of said pins being disposed in a grooved portion 196 formed in each of the sides of the raised portion 28 confronting said side walls. It will be understood that the closed bottoms of said grooves provide bearing surfaces for said pins 192. Spring 184 in chamber 40 is mounted between the movable contact member thereof and the casing portion 28 and the other of said springs in chamber 38 is mounted between the movable contact member thereof and the adjacent side wall 32 of the casing, said latter spring having end 188 thereof mounted in the groove 194 formed in the side wall 32 and said former spring having end 188 thereof mounted in a groove 196 formed in said portion 28. The other end 190, of each of said springs, engages the companion movable contact member 68 extending between the companion insulated portions 70 and 72 thereof, as illustrated. It will be understood that said springs 184 and 186 bias the movable contact members for rotation in a counterclockwise direction to the open circuit condition thereof. 60 Spring 198 is a handle-return spring and biases the handle to the "off" position thereof. As here shown, said spring is a helical spring disposed on the handle pivot pin 110. One end 200 of spring 198 is secured in the wall 32 of the casing part 24 and the other end 202 is secured in portion 184 of the handle link 100. It will be understood that in the "on" position, illustrated in Fig. 15, the combined tensions of springs 184, 186 and 198 70 are insufficient to break the toggle. In all other

respects said modified circuit breakers operate substantially in the same manner as the previously described circuit breakers.

Certain of the features disclosed herein are claimed in my copending application Serial No. 234,297, filed June 29, 1951.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent, is:

1. A multi-pole circuit breaker having a circuit breaker mechanism for each pole thereof, said mechanisms each having a movable contact member, actuating means and a flexible member bodily carried by and movable with said contact member and operable to latch said actuating means to the contact member and to unlatch the same by deflection of the flexible member, said actuating member being pivotally mounted on said contact member and moving relative thereto upon the tripping thereof to a predetermined disposition relative to the companion flexible member, and means interconnecting said actuating means to concomitantly move in one operation all of said mechanisms to the closed condition thereof from the tripped disposition thereof.

2. In a multi-pole circuit breaker having a circuit breaker mechanism for each pole thereof, said mechanism having a movable contact member, actuating means and a flexible member bodily carried by and movable with said contact member and operable to latch said actuating means to the contact member and to unlatch the same by deflection of the flexible member, said actuating means being pivotally mounted on said contact member and moving relative thereto upon the tripping thereof to a predetermined disposition relative to the companion flexible member, and means in operative engagement with said actuating member to concomitantly move in one operation all of said mechanisms to the closed condition thereof from the tripped disposition thereof comprising means interengaging said actuating means, and manually operable means in engagement with said interengaging means for operating the latter to pivot said actuating means into engagement with the companion flexible members.

3. In a multi-pole circuit breaker having a circuit breaker mechanism for each pole thereof, said mechanism having a movable contact member, actuating means, and a flexible member bodily carried by and movable with said contact member and operable to latch said actuating means to the contact member and to unlatch the same by deflection of the flexible member, said actuating means being pivotally mounted on said contact member and moving relative thereto upon the tripping thereof to a predetermined disposition relative to the companion flexible member, and means in operative engagement with said actuating means to concomitantly move in one operation all of said mechanisms to the closed condition thereof from the tripped disposition thereof comprising means interengaging said actuating means, and manually operable means in engagement with said interengaging means for operating the latter to pivot said actuating means into engagement with the companion flexible members, said manually operable

means comprising toggle means having one end in engagement with said interengaging means, and a manually operable member at the other end of said toggle for oversetting the latter whereby said toggle is operative to move all of said actuators into latched engagement with the companion flexible members for moving said contact members to the circuit closed condition thereof.

4. In a multi-pole circuit breaker having a circuit breaker mechanism for each pole thereof, said mechanism having a movable contact member, actuating means, and a flexible member bodily carried by and movable with said contact member and operable to latch said actuating means to the contact member and to unlatch the same by deflection of the flexible member, said actuating means being pivotally mounted on said contact member and moving relative thereto upon the tripping thereof to a predetermined disposition relative to the companion flexible member, and means in operative engagement with said actuating means to concomitantly move in one operation all of said mechanisms to the closed condition thereof from the tripped disposition thereof comprising means interengaging said actuating means, and manually operable means in engagement with said interengaging means for operating the latch to pivot said actuating means into engagement with the companion flexible members, said manually operable means comprising toggle means having one end in engagement with said interengaging means and a manually operable member at the other end of said toggle for oversetting the latter whereby said toggle is operative to move all of said actuators into latched engagement with the companion flexible members for moving said contact member to the circuit-closed condition thereof, said toggle means comprising rigid link means carried by said manually operable member and link means mounted for pivotal resilient movement therein, said interengaging means being mounted for pivotal movement on said latter link means, each of said mechanisms being biased to the open condition thereof, said toggle means opposing said bias in the closed condition of said mechanisms, and said interengaging means being pivoted by the movement of said actuating means upon the tripping of the mechanism thereof to aid the first mentioned bias in another of said mechanisms for tripping the latter.

5. In a multi-pole circuit breaker having a circuit breaker mechanism for each pole thereof, said mechanism having a movable contact member, actuating means and a flexible member bodily carried by and movable with said contact member and operable to latch said actuating means to the contact member and to unlatch the same by deflection of the flexible member, said actuating means being pivotally mounted on said contact member and moving relative thereto upon the tripping thereof to a predetermined disposition relative to the companion flexible member, and means in operative engagement with said actuating means to concomitantly move in one operation all of said mechanisms to the closed condition thereof from the tripped disposition thereof, comprising means interengaging said actuating means, and manually operable means in engagement with said interengaging means for operating the latter to pivot said actuating means into engagement with the companion flexible members, said manually operable means comprising toggle means having one end in engagement with said interengaging means and a manually operable member at the other end of said toggle for oversetting the latter whereby said toggle is operative to move all of said actuators into latched engagement with the companion flexible members for moving said contact members to the circuit closed condition thereof, said toggle

means comprising rigid link means carried by said manually operable member and link means mounted for pivotal resilient movement therein, said interengaging means being mounted for pivotal movement on said latter link means, each of said mechanisms being biased to the open condition thereof, said toggle means opposing said bias in the closed condition of said mechanisms, and said interengaging means being pivoted by the movement of said actuating means upon the tripping of the mechanism thereof to aid the first mentioned bias in another of said mechanisms for tripping the latter.

6. In a multi-pole circuit breaker, a pair of circuit breaker mechanisms, each having a movable switch member, actuating means therefor and a control member operable to latch said actuating means to the switch member and to unlatch the same upon overload, common means for concomitantly operating both of said switch members comprising means interconnecting said actuating means, and manually operable means having a connection with said interconnecting means for conjoint manual operation of said switch members.

7. In a multi-pole circuit breaker, a pair of circuit breaker mechanisms, each having a movable contact member, actuating means pivotally mounted thereon and a flexible member bodily carried by and movable with said contact member and operable to latch said actuating means to the contact member and to unlatch the same by deflection of the flexible member, common means for concomitantly operating both of said actuating means comprising means linking said actuating means and manually operable means in operative engagement with said linking means, said manually operable means comprising a toggle, said linking means being carried by one end of said toggle.

8. In a multi-pole circuit breaker, a pair of circuit breaker mechanisms, each having a movable contact member, actuating means pivotally mounted thereon, and a flexible member bodily carried by and movable with said contact member and operable to latch said actuating means to the contact member and to unlatch the same by deflection of the flexible member, common means for concomitantly operating both of said actuating means comprising means linking said actuating means and manually operable means in operative engagement with said linking means, said manually operable means comprising a toggle, said linking means being carried by one end of said toggle, said contact members being biased for movement from the closed condition thereof and said toggle opposing said bias, said linking means being pivoted upon the tripping of one of said mechanisms to aid the first mentioned bias in the other of said mechanisms for tripping the latter.

9. Actuating means for a multi-pole circuit breaker having a plurality of movable contact members normally biased for movement to the circuit-open condition thereof, each provided with a lever pivotally mounted thereon and carrying a flexible member in normal engagement with said lever to prevent relative pivotal movement, said actuating means comprising link means resiliently mounted for movement to and from an operative position for biasing said movable members to the circuit closed condition, and a link member carried for pivotal movement by said link means, said link member having each end thereof pivotally engaged in one of

said levers and being retained thereby in pre-determined disposition relative to said link means in the circuit closed condition and being released for the pivotal movement thereof upon the disengagement of a flexible member from one of said levers upon the tripping of a companion contact member for pivoting in a direction in opposition to the bias of said resilient link means whereby said first mentioned bias on another of said contact members is effective to trip the latter.

10. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof.

11. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members.

12. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including universal joint means.

13. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, means extending between

said poles and operable upon the release of a movable switch member at one of said poles from its actuator under the control of the control device at said one pole to effect movement of a movable switch member at another of said poles to circuit-interrupting position thereof, and spring means acting on each movable switch member to provide contact pressure at each pole in the circuit-closed condition of the circuit breaker.

14. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including means acting on each movable switch member to provide contact pressure at each pole in the circuit-closed condition of the circuit breaker.

15. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including means acting on each movable switch member to provide contact pressure at each pole in the circuit-closed condition of the circuit breaker.

16. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including resilient means acting on said actuators and through the latter on said movable switch members.

17. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including spring means acting on each movable switch member through said interconnecting means and actuators to provide

contact pressure at each pole in the circuit-closed condition of the circuit breaker.

17. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including universal joint means, and resilient means acting on said universal joint means for applying contact pressure for the contacts of each pole when the circuit breaker is closed.

18. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including universal joint means, a lost motion connection between said manually operable means and said universal joint means, and resilient means acting on said lost motion connection for applying contact pressure for the contacts of each pole when the circuit breaker is closed.

19. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including link means interconnected between said manually operable means and said interconnecting means.

20. A multi-pole circuit breaker having a movable switch member for each pole, an actuator for each movable switch member, a control device for each movable switch member to connect the companion actuator releasably thereto and

to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including link means interconnected between said manually operable means and said interconnecting means.

21. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including link means interconnected between said manually operable means and said interconnecting means, and a universal joint between said link means and said interconnecting means.

22. A multi-pole circuit breaker having a movable switch member for each pole, an actuator for each movable switch member, a control device for each movable switch member to connect the companion actuator releasably thereto and to disconnect the actuator from the companion movable switch member, means for moving the released movable switch member to circuit-interrupting position, and means interconnecting said actuators and operable upon the release of a movable switch member at one of said poles from its actuator under the control of the control device at said one pole to effect movement of a movable switch member at another of said poles to circuit-interrupting position thereof, and manually operable means having a connection with said interconnecting means for conjoint manual operation of said movable switch members, said connection including link means interconnected between said manually operable means and said interconnecting means, and resilient means acting at the connection between said link means and said manually operable means to provide contact pressure at each pole in the circuit-closed condition of the circuit breaker.

23. Actuating means for a plurality of circuit breaker mechanisms each of which is provided with an actuator, comprising means intercon-

necting said actuators for effecting conjoint operation thereof for closing said mechanisms, manually operable toggle means, and a universal joint connecting said toggle means to said interconnecting means for operation of the latter by said toggle means.

24. Actuating means for a plurality of circuit breaker mechanisms each of which is provided with an actuator, comprising means interconnecting said actuators for effecting conjoint operation thereof for closing said mechanisms, manually operable toggle means, and a universal joint connecting said toggle means to said interconnecting means for operation of the latter by said toggle means, said toggle means being effective when overset to releasably retain said mechanisms in the closed condition thereof, and resilient means acting upon said toggle means for providing contact pressure at said mechanisms, in said closed conditions thereof.

25. In an automatic circuit breaker having a stationary contact, a movable contact member having a contact engageable with and disengageable from said stationary contact, a current responsive latch, an actuator mounted on said contact member and operatively connected thereto, under the control of said latch, for closing the circuit breaker, a movable operating member and a link interconnected between said actuator and said operating member, that improvement which comprises a lost motion connection between said link and said operating member and means operable upon said lost motion connection when said actuator is latched to said movable contact member for biasing the latter whereby to provide for proper contact pressure between said contacts in the closed condition of the circuit breaker, said means being a resilient member connected between said lost motion connection and said operating member.

26. In an automatic circuit breaker having a stationary contact, a movable contact member having a contact engageable with and disengageable from said stationary contact, a current responsive latch, and an actuator mounted on said contact member and operatively connected thereto, under the control of said latch, for closing the circuit breaker, that improvement which comprises means cooperating with said actuator to form a toggle which when in overset relationship holds said contact member in its closed circuit position, a pivotal axis of said toggle being constituted by a lost motion connection, and resilient means connected between said operating member and said lost motion connection and operable upon the latter when said actuator is latched to said movable contact member for biasing the latter whereby to provide for proper contact pressure between said contacts in the closed condition of the circuit breaker.

27. In an automatic circuit breaker having a stationary contact, a movable contact member having a contact engageable with and disengageable from said stationary contact, a current responsive latch, an actuator mounted on said contact member and operatively connected thereto, under the control of said latch, for closing the circuit breaker, a movable operating member and a link interconnected between said actuator and said operating member, that improvement which comprises a lost motion connection between said link and said operating member and means operable upon said lost motion connection when said actuator is latched to said movable contact member for biasing the latter whereby to provide for

proper contact pressure between said contacts in the closed condition of the circuit breaker, said lost motion connection being constituted by a slot defined in said operating member and said link being provided with a part mounted for movement in said slot.

28. In an automatic circuit breaker having a stationary contact, a movable contact member having a contact engageable with and disengageable from said stationary contact, a current responsive latch, an actuator mounted on said contact member and operatively connected thereto, under the control of said latch, for closing the circuit breaker, a movable operating member and a link interconnected between said actuator and said operating member, that improvement which comprises a lost motion connection between said link and said operating member and means operable upon said lost motion connection when said actuator is latched to said movable contact member for biasing the latter whereby to provide for proper contact pressure between said contacts in the closed condition of the circuit breaker, said lost motion connection being constituted by a slot defined in said operating member and said link being provided with a part mounted for movement in said slot, and said means being a resilient member interconnected between said part and said operating member.

29. In an automatic circuit breaker having a stationary contact, a movable contact member having a contact engageable with and disengageable from said stationary contact, a current responsive latch carried by said movable contact member, an actuator mounted on said contact member and operatively connected thereto, under the control of said latch, for closing the circuit breaker, a pivotally movable operating member, that improvement which comprises a connection between said actuator and said operating member which includes a lost motion engagement between said operating member and said connection, and resilient means interconnected between said operating member and said lost motion engagement and through said lost motion engagement when said actuator is latched to said movable contact for biasing the latter whereby to provide for proper contact pressure between said contacts in the closed condition of the circuit breaker.

30. Actuating mechanism for a pair of companion automatic circuit breakers comprising an actuator for each circuit breaker for effecting manual operation of the associated breaker to circuit making and circuit interrupting conditions thereof, a universal joint interconnected between said actuators, and a manually operable member connected to said joint for concomittant manual operation of said actuators, whereby to effect concomittant manual operation of said circuit breakers for making and interrupting the circuits, respectively, thereof.

31. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and universal joint means interconnected between said actuators and operable upon release of one of said movable contact members from its actuator under the control of the control device at one pole to effect movement of

a contact member at another of said poles to its circuit-interrupting position.

32. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and universal joint means interconnected between said actuators and operable upon release of one of said movable contact members from its actuator under the control of the control device at one pole to effect movement of a contact member at another of said poles to its circuit-interrupting position, and manually operable means connected to said universal joint means for conjoint manual operation of the movable contact members.

33. A multi-pole circuit breaker having a movable contact member for each pole, an actuator for each movable contact member, a control device for each movable contact member to connect the companion actuator releasably thereto and to disconnect the actuator from the companion movable contact member, means for moving the released contact member to circuit-interrupting position, and manually operable means connected to said universal joint means for conjoint manual operation of the movable contact members.

rupting position, and means interconnected between said actuators and operable upon release of one of said movable contact members from its actuator under the control of the control device at one pole to effect movement of a contact member at another of said poles to its circuit-interrupting position, and manually operable means connected to said interconnected means for conjoint manual operation of the movable contact members, said connection of the manually operable means to said interconnected means having provision for acting on each movable contact member to provide contact pressure at each pole in the circuit-closed condition of the circuit breaker.

PAUL M. CHRISTENSEN.
